UNITED STATES PATENT OFFICE

DIDRICK DYRESEN, OF MALDEN, MASSACHUSETTS.

FASTENER.

Application filed January 16, 1926. Serial No. 81,870.

This invention aims to provide an improved fastener casing.

Reference is made to a divisional application, Serial No. 93,905, filed March 11th, 1926.

5 In the drawings, which illustrate two preferred embodiments of my invention:

Figure 1 is a front elevation of the first preferred form of casing;

Fig. 2 is a side elevation of the casing 10 shown in Fig. 1;

Fig. 3 is a rear elevation of the casing shown in Fig. 1;

Fig. 4 is a cross-section showing the manner in which the casing shown in Fig. 1 is 15 secured to a support;

Fig. 5 is a front elevation of the second preferred form of casing;

Fig. 6 is a side elevation of the second preferred form of casing;

20 Fig. 7 is a rear elevation of the casing shown in Fig. 6; and

Fig. 8 is a cross-section showing the manner in which the second preferred form of casing is secured to its support.

25 Referring to the drawings and to that form of my invention illustrated in Figs. 1 through 4, I have shown a flush type casing comprising a fastener socket formed from a single piece of metal and fastening 30 means formed integral with the casing for securing it to a support.

The casing illustrated includes a generally cylindrical body portion 1 having a reduced portion 2 toward its inner end, a flange 3 at the outer end of the casing, a front face 4 generally dished toward a stud-receiving aperture 5 and a rounded stud-engaging wall 6 surrounding the stud-receiving aperture. The casing also presents, 40 at its inner end, a plurality of attaching prongs 7 formed integral with the casing. In referring to the body portion 1 of the casing, I make reference to that portion which is adapted to enter an opening in the support apart from the flange 3. This body portion is formed into two diameters, one being of a size to fit an opening in a support and the smaller portion 2 being provided so that the prongs may be bent 45 outwardly initially for the purposes hereinafter described. These prongs, as illustrated in Figs. 2 and 3, extend from the edge of the reduced portion 2 and are initially bent outwardly from the casing so that 50 the outer ends thereof are substantially in line with the face of the largest portion of

the body portion 1. The prongs are preferably tapered to a point and are wedge-shaped thereby providing sharp pointed thin ends easily bendable.

60 The socket may be secured to the body 8 of an automobile, or other like support, by first drilling a hole in the body 8 of the car, preferably in the wooden frame part, to provide a casing-receiving recess. At 65 the bottom of the hole, I have provided an annular anvil portion 8^a, as illustrated in Fig. 4. The socket is then placed in the recess and the prongs 7 rest against the anvil portion so that, when pressure is applied 70 to the flange 3, the prongs will be forced outwardly by the anvil portion 8^a and pierce the wall surrounding the recess.

75 The prongs being initially bent and easily bendable toward their ends, are therefore curved outwardly when forced into the wooden part of the body 8, thereby hooking themselves into the body 8 to secure the socket thereto so that the ordinary outward strains exerted thereon, when a stud is locked in the 80 socket, will not pull the prongs 7 free from the wooden support. Any strain exerted upon the casing would be so remote from the prongs and so unevenly exerted thereupon that the prongs would hold fast.

85 The form of attachment herein described and illustrated by the drawings (Figs. 1 through 4) may be equally useful in securing any casing part of a separable fastener to a wooden support, and is not necessarily 90 limited to use in connection with the socket part of a separable fastener. The only portion of the socket which extends beyond the side of the body 8 is, therefore, the flange 3, which, being of greater diameter than 95 the body portion 1 of the socket, covers the edge of the socket-receiving recess and presents a neat and finished appearance.

100 Referring to the second form of casing illustrated in Figs. 5 through 8, I have shown a fastener socket similar, in construction, to the one shown and described in the first form of socket. This casing is provided with a series of apertures 10 (Fig. 6) spaced about the body portion 1 to provide a plurality of attaching elements 11 therebetween. When securing this socket to the supports 8, I first place the casing into the aperture therein until the inner end thereof 105 seats against the wooden body portion 8 at the bottom of the recess. The flange 3 is spaced slightly away from the front face of

the body 8, but when pressure is applied thereto it is forced against the front face of the body, as illustrated in Fig. 8. During the above-mentioned operation, the metal 5 of the casing between the apertures 10 is distorted outwardly to form the attaching elements 11. The casing collapses between the apertures 10, and the attaching elements 11 are forced into the wall of the recess to hold 10 the socket casing in place, as shown in Fig. 8.

While I have shown and described two preferred embodiments of my invention, it will be understood that I have done so merely for clarification and that my invention 15 is best defined in the following claims.

I claim:

1. A flush type casing element including a body part presenting at the inner end thereof a plurality of attaching prongs 20 adapted to be bent outwardly from said casing to engage a rigid support when said casing is forced into a recess presented by the support and a flange at the other end adapted to seat against the outer face of the support.

2. A flush type socket casing installation comprising, in combination, a rigid support presenting a recess therein having an anvil portion at the bottom of said recess, a socket 30 casing presenting at one end thereof a flanged portion and a stud-receiving aperture and at the other end a plurality of attaching prongs bent outwardly into the support by said anvil portion to secure said casing to the support.

3. In a fastener installation, a fastener element comprising a casing presenting means at one end thereof for engagement with a cooperating fastener element a flange 40 at the same end and a plurality of attaching

parts extending from said casing at the other end curvilinearly into a wooden support to secure said casing thereto.

4. A fastener element comprising a casing presenting means at one end thereof for engagement with a cooperating fastener element, a flange at the same end for engagement with one face of a support and a plurality of attaching prongs extending from said casing, said prongs being initially bent 50 before securing the casing to the support.

5. A flush type socket casing formed from a single piece of metal and presenting at one end of the body of said casing a plurality of initially outwardly bent attaching elements 55 and at the other end a flange and a stud-receiving aperture.

6. A flush type socket comprising a casing having a body portion of two diameters, a plurality of initially bent attaching prongs 60 extending outwardly from the end of the smaller of the two portions of said body portion and terminating in a plane parallel with the largest diameter of the body portion thereby to permit said body portion to be forced into an aperture in a support of substantially the same diameter as the largest diameter of said body portion, and a flange at the other end of the body portion.

7. A flush type socket comprising a one-piece casing for application to a wooden support, said casing presenting a plurality of attaching portions adapted to be pressed into the support to secure said casing thereto and a flange at the outer end of said casing for limiting the inward movement of said casing relative to said support.

In testimony whereof, I have signed my name to this specification.

DIDRICK DYRESEN.
